United States Patent Office

Des. 186,902
Patented Dec. 22, 1959

186,902

ROASTING PIN

Robert P. Fried, Staatsburg, N.Y.

Application January 27, 1959, Serial No. 54,344

Term of patent 14 years

(Cl. D44—29)

FIG. 1

FIG. 2

FIG. 3

Fig. 1 is an elevational view of a roasting pin showing my new design;

Fig. 2 is a top plan view; and

Fig. 3 is a bottom plan view.

I claim:

The ornamental design for a roasting pin, substantially as shown.
